ATTORNEY

UNITED STATES PATENT OFFICE.

WILLIAM P. GRANT, OF SAN JOSE, CALIFORNIA.

ADJUSTABLE GAS-PLATE.

1,372,419.

Specification of Letters Patent. Patented Mar. 22, 1921.

Application filed June 8, 1920. Serial No. 387,470.

To all whom it may concern:

Be it known that I, WILLIAM P. GRANT, a citizen of the United States, and resident of San Jose, in the county of Santa Clara and 5 State of California, have invented certain new and useful Improvements in Adjustable Gas-Plates, of which the following is a specification.

My invention relates to a gas plate mounted to be turned into an inoperative position 10 against a wall.

It is the object of my invention to provide a device of the character indicated in which a gas plate operatively connected to a gas 15 supply may be readily turned into an inoperative position against a wall or inclosed in a compartment prepared therefor, at the same time cutting off the gas supply thereto and as readily positioned for use at the same 20 time automatically opening the gas supply thereto. A further object is to provide a device of the character indicated which will be simple in arrangement, construction and operation, and particularly adapted to be 25 fitted into or upon the wall of a room, the closure or door for the inclosing compartment acting as a support for the plate when in use.

In the drawing:—

30 Figure 1 is a plan view of my invention operatively mounted in a compartment in a wall.

Fig. 2 is a sectional view on line 2—2 of Fig. 1.

35 Fig. 3 is an enlarged detail section through the supply pipe joint.

Fig. 4 is a side elevation of another embodiment of my invention.

Fig. 5 is a plan view of the embodiment 40 shown in Fig. 4.

Referring more particularly to the drawing 1 indicates a compartment in a wall fitted with door 2 on hinges 3. At 4 is a bracket supported in compartment 1 a distance from the back thereof and having a gas plate 5 revolvably mounted thereon by 45 hinges 6.

Plate 5 is provided with front legs 7 weighted at 8 and provided with rollers 9, 50 the latter operating on tracks 10 secured to door 2. The door 2 is held in a horizontal position when open by means of arms 11 secured to the lower end thereof and engaging blocks 12 secured to the wall of compartment 1 as shown. The arms 11 are

preferably bent as at 13 to prevent their extending out of the compartment when the door is closed, and weighted as at 14 to act as a counterbalance for the said door.

The plate 5 is fitted with a gas supply pipe 60 15 in the usual manner and passing backwardly along one end thereof to a joint 16 in axial alinement with hinges 6. Joint 16 is formed by fitting a member 17 on a fixed tapering supply pipe 18 provided with an 65 orifice 19. Member 17 communicates with pipe 15 through passage 20 and revolves on pipe 18, being held thereon by nuts 21.

In operation when the door 2 is lowered and held in a horizontal position the rollers 70 9 operate on tracks 10 until the plate 5 assumes a horizontal position. This lowering of the plate automatically revolves member 17 on supply pipe 18 so that orifice 19 communicates with pipe 15 thereby permitting 75 the gas to flow. When the door 2 is closed the plate is turned back into the compartment 1 and member 17 is revolved on supply pipe 18 so that the communication between passage 20 and orifice 19 is broken 80 and the flow of gas is interrupted.

In Figs. 4 and 5 it is shown that substantially the same mechanism may be used to mount the device on a flat wall, but brackets 22 pivotally connected to plate 5 85 and provided with shoes 22^a operating in vertical track 23 are used instead of the door support hereinbefore described. In this case the ends 24 of tracks 23 are used as supports for the sliding brackets 22. 90

A pan 25 having a raised rear edge 26 is placed on door 2 to prevent sliding of material from the door into compartment 1 when the same is closed.

I claim:

A wall compartment, a counterbalanced door hingedly mounted on the front lower edge thereof, tracks mounted thereon in parallel relation to the side edges thereof, a bracket mounted in said compartment, a gas 100 plate hingedly, mounted thereon, weighted legs on the forward portion of said plate adapted to engage said tracks, a fixed gas supply pipe having a discharge head in axial alinement with said bracket, and gas 105 connections to said plate revolvably mounted on said fixed head and in communication therewith.

WILLIAM P. GRANT.
